UNITED STATES PATENT OFFICE.

HAROLD BRIX, OF ARLINGTON HEIGHTS, ILLINOIS, ASSIGNOR TO SHARP & SMITH, OF CHICAGO, ILLINOIS, A CORPORATION OF ILLINOIS.

ANASTOMOSIS CLAMP.

1,413,896.

Specification of Letters Patent. Patented Apr. 25, 1922.

Application filed April 16, 1921. Serial No. 461,798.

To all whom it may concern:

Be it known that I, HAROLD BRIX, a citizen of the United States, residing at Arlington Heights, in the county of Cook and State 5 of Illinois, have invented a new and useful Improvement in Anastomosis Clamps, of which the following is a specification.

My invention relates more particularly to anastomosis clamps for use in connection 10 with operations on the intestines and the stomach and more especially to the type of clamp comprising a centrally-disposed bar member, a pair of bars located at opposite sides of the centrally-disposed member, and 15 means carried by the latter for engaging the outer ends of the pairs of bars and releasably hold them in adjusted position relative to the central bar. A method commonly practiced in connection with instruments of 20 this character consists in the making of an incision in the stomach or intestines adjacent to the portion thereof to be operated on, and the insertion of the central bar member 25 through the incision, and thereafter the swinging of the pair of bars referred to, toward the central bar and the securing together of these bars at their outer ends to effect the desired clamping to the device, of the tissues thus engaged by the device.

30 In the use of devices of this character, it is highly desirable that they be so constructed that they may be quickly and accurately manipulated. Furthermore, in the application of the device to use and its removal from 35 the patient, it is necessary that the tightening means referred to and carried by the central bar member be so positioned that they will not present obstruction to the ready application and removal of the device.

40 One of my primary objects is to provide improvements in devices of the character stated, whereby the devices carried by the central bar member for engaging and holding in clamping position, the clamping bars disposed at opposite sides thereof, may be moved into a position in which they will not 45 obstruct the application of the device to use and its removal, and will be so lined up with the portions of the outer bars with which 50 they cooperate, that they will be properly automatically guided into position for clamping. A further object is to restrict the swinging movement of the tightening devices so that these devices will be restrained 55 from swinging from a position in which they

are alined with the bar carrying them, except in a direction for engaging with the respective outside bars with which they cooperate; and other objects as will be manifest from the following description.

60 Referring to the accompanying drawing: Figure 1 is a view in elevation of a clamp constructed in accordance with my invention. Figure 2 is an enlarged plan view of the upper end of the clamp. Figure 3 is a view 65 in side elevation of the upper portion of the clamp device, showing the devices employed for holding the bars in clamping position, in the folded position they occupy in the application of the instrument to a patient and its 70 removal from a patient. Figure 4 is a similar view of the structure shown in Fig. 3, viewing the structure from the right hand side of this figure. Figure 5 is a face view 75 of the upper end of one of the outside clamping bars; and Figure 6, a broken view in elevation of the device of Fig. 1 viewing it from the right hand side of the latter.

75 In the particular construction illustrated the device is formed of a central bar portion 80 shown as terminating in a handle 8, the bar portion 7 being provided with the enlargement 9 apertured as indicated at 10. The outer end of the bar 7 contains a recess 11 85 in which a pin 12 is mounted, this pin serving as a pivotal support for a pair of tightening devices 13. The devices 13 comprise the shanks 14 threaded at opposite edges as indicated at 15, the edges which extend generally in a plane parallel with the plane in which the pin 12 extends, and with their other opposed surfaces flat as indicated. Threaded on each of the shanks 14, is a wing-nut 16 presenting a generally circular 90 lower end 17, the outer ends of the devices 13 being of spherical form as represented at 18. Surrounding the pin 12 and located between the side walls 19 of the recess 11, and the outer surfaces of the shanks 14, are coiled 95 springs 20 which are preferably under relatively light tension and which operate to center the shanks 14 in the space between the walls 19, but are yieldable outwardly when the devices 13 are swung to the position shown in Figs. 3 and 4, the openings in the shanks 14 and through which the pin 12 extends being sufficiently large to permit the devices 13 to assume the canted position 100 shown in Fig. 4.

105 Cooperating with the bar 7 and the tight- 110

ening devices 13 referred to, is a pair of bars 21 preferably of spring metal which are pivotally connected at their lower ends with the bar 7 by means of a pin 22, these bars 5 being provided at their lower ends with offset circular portions 23, through which the pin 22 extends and which flatwise oppose each other, to afford a desirable pivotal support for the bars 21. The extremities of the 10 bar 7 contain notches 24 adapted to receive the shanks 14, the outer surfaces of these bars at their slotted portion being dished as represented at 25 to conform generally to the curved portions 17 of the nuts 16 thereby 15 forming sockets preventing accidental disengagement of the fastening devices 13 from the notched portions 24 of the bars 21.

Referring particularly to Fig. 2, it will be noted that the devices 13 which extend in 20 opposite directions from the bar 7 are offset relative to each other, and as the bars 21 are preferably located in the same plane as shown in Fig. 2, the slots 24 are offset in the bars 21 to line up with the respective shanks 25 14, in order that the shanks 14 will, when these securing devices are thrown over to securing position, readily enter the respective notches 24.

It is desirable that means be provided for 30 preventing the tightening devices 13 from swinging outwardly beyond a position in which they aline with the central bar 7, the means shown for this purpose comprising a projection 26 on each of the shanks 14 which, 35 when the tightening devices are swung to a position in alinement with the bar 7, engage the bottom wall 27 of the recess 11 and thus form stop-means limiting the movement of these tightening devices. It is thus impossible 40 for either one of the tightening devices to swing to one side of the bar 7 opposite that at which the slot with which it cooperates, extends, with the manifest advantage.

45 In the use of the device the operator, prior to introducing the bar portion 7 through an incision, would swing the tightening devices 13 to the position shown in Figs. 3 and 4 in which position the springs 20 are placed 50 under tension and serve to hold the parts in the position shown permitting the bar portion 7 to be inserted through the incision without danger of the tightening devices moving to a position in which they would 55 obstruct the proper insertion of the device into the desired position. In this connection it may be stated that the openings in the shanks 14 through which the pin 12 extends, are of slightly greater diameter than 60 the diameter of the pin whereby these shanks may, in the movement of the devices 13 to the alined position shown in Figs. 3 and 4, move in the plane of the pin or, in other words, assume the canted position shown in 65 Fig. 4 against the tension of the springs 20.

Following the introduction of the bar portion 7 through the incision as stated, the outside bars 21 are swung toward the middle bar 7 to clamp the tissues at the opposite sides of the incision, between the bar 7 and 75 the bars 21, the devices 13 then being swung outwardly and downwardly to a position in which the shanks 14 enter the notches 24, whereupon the wing-nuts 16 are tightened 80 against the bars 21, seating at their curved portions 17 in the socket portions 25 of these bars, the operator screwing up these nuts to effect the desired tension on the tissues clamped by the device. It will be noted that either one of the bars 21 may be released independently of the other as conditions may render it desirable.

The springs 20 tend to center the devices 13 in the recess 11 and when these devices are swung downwardly and outwardly from 85 the position shown in Figs. 3 and 4, they will be caused to accurately aline with the notches 24 with which they cooperate and thereby insure their entry into the notches without requiring any centering by the operator.

While I have illustrated and described a particular construction embodying my invention, I do not wish to be understood as intending to limit it thereto, as the same 95 may be variously modified and altered without departing from the spirit of my invention.

What I claim as new, and desire to secure by Letters Patent, is:

1. In a device of the character set forth, the combination of a middle bar, a pair of bars located at opposite sides of said middle bar, said bars being relatively movable, tightening devices for engaging said pairs of 105 bars pivoted side by side on the outer end of said middle bar to swing upon said pivot and relatively movable on said pivot in the plane of the latter, and spring means resisting relative movement of said devices in the 110 plane of said pivot.

2. In a device of the character set forth, the combination of a middle bar, a pair of bars located at opposite sides of said middle bar, said bars being relatively movable and 115 said pairs of bars containing notches in their outer ends, tightening devices pivoted side by side on the outer end of said middle bar to swing upon said pivot and relatively movable on said pivot in the plane of the latter 120 and adapted to enter said notches and engage said pairs of bars, and spring means resisting relative movement of said devices in the plane of said pivot.

3. In a device of the character set forth, 125 the combination of a middle bar, a pair of bars located at opposite sides of said middle bar, said bars being relatively movable, the outer end of said middle bar containing a recess, a pin extending across said recess, 130

tightening devices for engaging said pairs of bars pivoted side by side on said pin to swing upon said pin, said recess being longer than the combined thickness of said devices 5 and said devices being relatively movable on said pin in the plane of the latter, and spring means interposed between the end-walls of said recess and said tightening devices, for the purpose set forth.

- 10 4. In a device of the character set forth, the combination of a middle bar, a pair of bars located at opposite sides of said middle bar, said bars being relatively movable and said pairs of bars containing notches in their 15 outer ends, tightening devices pivoted side by side on the outer end of said middle bar to swing upon said pivot and relatively movable on said pivot in the plane of the latter, said devices comprising threaded shanks at 20 which portions they are pivoted and at which they extend into said notches, and nuts screwing upon said shanks and against said pairs of bars, and spring means resisting relative movement of said devices in the 25 plane of said pivot.

5. In a device of the character set forth, the combination of a middle bar, a pair of bars located at opposite sides of said middle

bar, said bars being relatively movable, and tightening devices for engaging said pairs 30 of bars pivoted side by side on the outer end of said middle bar to swing upon said pivot, and stop means limiting said devices each to rotation on said pivot in one direction only beyond a position in which they aline with 35 said middle bar.

6. In a device of the character set forth, the combination of a middle bar, a pair of bars located at opposite sides of said middle bar, said bars being relatively movable and 40 said pairs of bars containing notches in their outer ends offset relative to each other, the outer end of said middle bar containing a recess, a pin extending across said recess, tightening devices comprising threaded 45 shanks pivoted side by side on said pin and nuts screwing on said shanks, the length of said recess being greater than the combined thickness of said shanks, said devices being movable on said pin in the plane of movement of said pin and said shanks being adapted to enter said notches and said nuts 50 to engage said pairs of bars, and springs located between the end-walls of said recess and said pairs of bars.

HAROLD BRIX.
